UNITED STATES PATENT OFFICE

JAMES A. MOORE, OF ROCHESTER, PENNSYLVANIA

SPACING MECHANISM

Application filed June 15, 1927. Serial No. 199,023.

The present invention relates to a spacing mechanism and more particularly to a mechanism adapted for accurately spacing iron and steel shapes and the like for punching or stamping.

5 I provide a mechanism embodying accurate and positive stop means enabling duplicate pieces to be punched or stamped with great accuracy. I further provide a spacing mechanism capable of being quickly adjusted from one character of spacing to another, and also from one character of material to another.

10 My spacing mechanism is particularly adapted for spacing relatively light structural shapes or strips to enable a single operator to manipulate a punching or stamping press and quickly and accurately punch or stamp duplicate pieces.

In the drawings:

20 Figure 1 is a side elevation of a spacing machine embodying my invention;

Figure 2 is an enlarged side elevation of the carriage of the machine shown in Figure 1;

25 Figure 3 is a top plan view of the carriage shown in Figure 2;

Figure 4 is a diagrammatic perspective view of the gag and the various elements operating on the gag;

Figure 5 is a sectional view showing the carriage in end elevation;

30 Figure 6 is a back elevation of a portion of a machine;

Figure 7 illustrates the linkage employed to adjust the roll supporting stands;

25 Figure 8 is an end elevation of the linkage shown in Figure 7, the control members being in cross-section;

Figure 9 illustrates the adjusting mechanism for varying the height of the supporting rolls;

Figure 10 diagrammatically shows the operating connection between the punch and the spacing mechanism;

40 Figure 11 shows the preferred operating cam and roller for the connection illustrated in Figure 10;

Figure 12 is a top plan view of the preferred form of stop;

45 Figure 13 is a back elevation of the stop shown in Figure 12;

Figure 14 is a sectional view showing the stop in engagement with the rack bar;

Figure 15 is a detail of the dogs employed in the gag locking mechanism;

50 Figure 16 is a side elevation of the dog shown in Figure 15;

Figure 17 is a sectional view of the gripper jaw operating mechanism; and

55 Figure 18 illustrates the preferred type of cam for operating the gripper jaw controlling mechanism.

Referring to the illustrated embodiment, there is shown in Figure 1, a spacing mechanism comprising a carriage indicated generally by the numeral 2. The carriage 2 is movable along a horizontal track 3, supported by standards 4, only one of which shows in the drawing. A number of supporting standards 5 are spaced along and beneath the track 3, rolls 6 in the standards 5 being held at a suitable height for supporting material 7 to be spaced.

70 In the operation of the machine, a strip of material 7 supported at a suitable height by the rolls 6, is moved along the track 3, clamped in the carriage 2. The carriage 2 is positively stopped at desired points along the track 3 while a punching or stamping operation is performed on the strips 7. After the stamping or punching operation has 75 been completed, the carriage is free to move ahead for another predetermined interval. The automatic unlocking of the carriage is performed by a connection between the stamping mechanism and the punching or stamping machine, neither of which is shown in Figure 1, but will be illustrated and described more fully hereinafter.

Referring to Figure 2, there is shown a carriage comprising a frame 8, having supporting rollers 9 and 10 thereon. Supported by the frame 8 is a jaw supporting member 11 which is spaced outwardly from the frame by brackets 12. A jaw 13 is secured to the outer end of the member 11, so that material to be operated upon is held at a point spaced from the carriage and consequently from the track 3. This permits the supporting rolls 6 (Figure 1) to be advantageously disposed without interfering with 85

the track 3. Mounted directly above the jaw 13 is a movable jaw 14 having an adjustable set screw 15 mounted therein for cooperation with the strip to be gripped. 5 The jaw 14 is disposed at the end of a lever 16, pivotally supported by the member 11. The member 16 is normally urged in such direction that the jaws 13 and 14 are spread apart by a spring 17 coiled around a guide 10 rod 18, abutting the shank of the jaw 13. The jaws are closed by a member 19 operating between the chamfered end 20 of the lever 16 and a cam surface 21 supported by the jaw supporting member 11. The effect 15 of the oppositely disposed chamfered surface 20 and the cam surface 21 is to form a wedge shaped opening into which the operating member 19 may be thrust by links 22, effectively closing the jaws 13 and 14 by 20 reason of the powerful wedging action afforded and the mechanical advantage of the lever 16. The operating member 19 is normally retracted from the opening between the lever 16 and the cam surface 21 25 by a spring 23 connected to a stirrup 24 engaging a pin 25 by which the links 22 are connected to the operating member 19. When the member 19 is retracted, as shown in Figure 2, the spring 17 holds the jaws 30 13 and 14 apart for the ready insertion of material to be spaced.

The links 22 are pivoted upon a bracket 26 extending from the frame 8. Intermediate the pivot point and the pin 25, the links 35 22 are engaged by a pin 27 fixed in a bar 28 which extends between the links 22 and is supported by a bracket 29 secured to the frame 8 and extending through a slot 30 in the bar 28. The links 22 are normally held 40 in contact with the pin 27 by the spring 23.

Movement of the bar 28, causing forward movement of the member 19, and closing of the jaws, is effected by a cam block 31, having a generally cylindrical shape (Figure 45 18) with cam surfaces cut on both ends thereof. The cam surfaces cooperate with cam followers 32 and 33, the followers 32 being fastened into a block 34 in which the bar 28 terminates. The followers 33 are 50 fitted into a cylindrical barrel 35 slidably mounted in a supporting cylinder 36. The cylinder 36 is fastened to the frame 8 of the carriage by a supporting bar extending from the frame. When the cam block 31 is rotated by a handle 37, the cam followers 32 55 and 33 are moved apart so that the pin 27 must move away from their position, or the cam block must move bodily to the left, as viewed in Figure 2. Movement of the cam block toward the left is resisted by a spring 38, housed within the cylinder 36. The spring 38 operates against the end of the barrel 35, the compression of the spring being adjusted by a threaded bushing 39 abutting 60 against a fitting 40 conforming to the

end of the spring 38. Slidably disposed within the bushing 39 is a threaded rod 41 which is attached to the barrel 35 at the one end and has a nut 42 bearing against the threaded bushing 39 at the other end. By 70 adjusting the nut 42 the spring 38 may be placed under any desired initial compression. The position of the bushing 39, with respect to the cylinder 36, determines the normal position of the barrel 35 with respect to the cylinder. When the cam block 31 is rotated, the bar 28 is moved forwardly until the member 19 has been thrust into the wedge shaped opening between the lever 16 and the cam surface 21 an amount sufficient 75 to close the jaws upon the material to be gripped; when the jaws become stationary, further movement of the cam block 31 forces the barrel 35 into the cylinder 36 compressing the spring 38, thus the jaws securely 80 grip the material even though repeated shocks of the punching or stamping machine upon the material should cause slight deformation of the material at the jaws. The barrel 35 is maintained from rotation, when 85 the cam block 31 is rotated, by means of a pin 43 operating in a slot 44 in the cylinder 36. Rotation of the bar 28 is prevented by reason of the bracket 29 extending through the slot 30 in the bar 28. 90

The bar 28 is guided by the bracket 29 extending into the slot 30 and also by a rod 45 threaded into the block 34 and extending through the cam block 31 into the barrel 35. The rod 45 serves as a bearing for the cam 100 block 31.

As shown in Figure 18, the cam block 31 is preferably provided with cam surfaces on both ends, there being two cam surfaces on each end. Provision of cam surfaces on both ends of the block 31 permits considerable travel of the cam followers in a 90° rotation of the cam block. The ends of the block 31 have flat portions 46 intermediate the cam surfaces upon which the cam followers rest when the jaws are in closed position. The cam action is, therefore, non-reversible and a simple downward movement of the handle 37 effectively locks the jaws in closed position, the spring 38 being effective for maintaining a tight grip in case the set screw 15 works deeper into the material under the shocks of repeated movement of the material. 110

The construction just described, with the cam block 31 in line with the spring 38, provides a compact structure in which rotation of the cam block increases the effective length of the separating cam 31 so that links 22 must move away from the spring 38 and further compression of the spring will result. The spring 38 is preloaded so that the motion imparted by the cam block simply operates to transfer the spring load to the jaws; the motion of the cam block does not in itself determine the biasing of the spring. 120 130

After the material has been gripped between the jaw 13 and the set screw 15 by a downward movement of the handle 37, the carriage is moved along the track in the direction of the arrow A in Figure 1. The carriage is movable freely along the track 3 in both directions as long as a gag 47 (Figure 3) is disengaged from stops 48 which are set in the bed of the framework supporting the track 3, as shown in Figure 5. The stops 48 (Figure 12) are provided with teeth 49 along one side thereof, the teeth being adapted to engage a rack bar 50 which extends the length of the track 3. The teeth 49 may be of any desired pitch, depending upon the spacing which is required, ordinarily an even division of an inch will be used, say one-eighth inch. The stop 48 is provided with a hinged arm 51 which has a set screw 52 extending completely through it and engaging the body portion of the stop. The arm 51 is hinged at the bottom of the stop upon a pin 53, the arm being disposed in a channel cut in the block so that when the set screw 52 is retracted the arm lies wholly within the body of the stop. The stop may then be inserted in a channel 54 formed between the rack bar 50 and a back plate 55. With the stop so inserted (Figure 14) the set screw 52 is turned up and the teeth 49 are forced snugly into the teeth on the rack bar, insuring an accurate positioning of the stop. The leading face 56 of the stop is the face which determines the position of the carriage. The gag 47 engages the face 56 in determining the spacing interval.

The gag 47 is slidable transversely of the carriage, being guided between guide blocks 57 and 58, a cover plate 59 being placed over the gag adjacent the stop engaging end. As shown in Figure 4, the stop engaging end 60 of the gag is provided with a knockout rod 61 extending axially of the gag. The rod 61 is adapted to be engaged by a tripper bar 62 (Figures 3 and 5) whereby the gag may be moved out of engagement with the stops, compressing a spring 63 coiled about a rod 64 pivotally connected to the opposite end of the gag from the knockout rod 61. The stop engaging end 60 is chamfered slightly as is the gag engaging face 56 of the stop, whereby reengagement of the gag with the same stop after disengagement is obviated, the gag being turned angularly by a rod 65 bearing against the side thereof to swing the gag in the guide blocks so that the chamfered end of the gag passes the chamfered face of the stop immediately upon the tripper bar 62 pushing the gag back sufficiently to clear the engaging faces. A spring 66 coiled about the rod 65, normally urges the gag to the left, as viewed in Figure 3. The rod 65 and spring 66 are disposed within a cylindrical opening in the bed of the

carriage, a screw plug 67 being effective for compressing the spring 66.

It will thus be seen that the gag is not positively retained in the guide blocks, but is normally urged into engagement with the stops by the spring 63 and is normally urged to an angular position by the spring 66. It will be noted that the guide blocks have straight portions 68 and 69, and angular faces 70 and 71. The gag, being rotatable slightly about an axis, substantially intermediate the lines formed by the intersection of the faces and straight portions.

With the mechanism just described, the carriage may be moved from stop to stop successively along the track 3 by operating a tripper bar 62 to disengage the gag from the stop. When the gag is disengaged from the stop, the carriage is moved by the operator, pushing on the material held in the jaws of the carriage. The tripper bar 62 is supported on brackets 72 which are mounted on an operating shaft 73. The shaft 73 is supported in bearing blocks 74 mounted on the track supporting structure. The shaft 73 (Figure 10) is provided with an arm 74, having a cam surface 75 (Figure 11) thereon. The cam surface 75 is engaged by a roller 76 supported on a bracket 77 connected to a punch 78 operating on the material 7. It will be seen from the drawings that each operation of the punch will result in the roller 76 operating the arm 74, whereby the shaft 73 is rotated and the tripper bar knocks the gag out of engagement with any stop with which it may be engaged.

If the gag were permitted to extend into engaging relationship with the stops, as shown in Figures 3 and 5, at all times, it would be inconvenient, if not impossible, to move the carriage toward the right, as viewed in Figure 3, because the gag would interfere with the stops. In order to obviate such a condition, and make the carriage freely slidable when moved to the right, as shown in Figures 1 and 3, I provide a locking mechanism whereby the gag is held out of any possible engagement with the stops after the carriage has been moved to the end of its effective operating travel. This is accomplished by means of a stud 79 protruding from the top of the gag 47. The stud 79 is adapted to be engaged by a locking pin 80 which is mounted in a slide bar 81 movable transversely above the gag in guides 82 which are secured to the carriage. The stud 79 is offset slightly from the midline of the gag 47 so that the locking pin will not engage the stud during the normal operation of the machine in the direction of the arrow A, in which case the slide bar 81 is moved to the extreme right position, as shown in Figure 3.

The stud and locking pin are both chamfered so that when the gag is moved by the tripper bar and the locking pin coincides

with the stud, the stud will raise the locking pin and pass beneath it, after which a spring 83 wound around the locking pin snaps the pin down behind the stud 79 and holds the gag so that the spring 63 will not force it back into a stop-engaging position. After the carriage has been returned to the extreme right position, and a new strip of material is to be operated upon, the slide bar 81 is moved to the right, as shown in Figure 3. Reciprocation of the slide bar 81 is effected by a crank 84 (Figure 4) mounted on a shaft 85 which is rotated by dogs 86 and 87. The bar 81 is maintained in its extreme right or left hand position by a spring 88 operating on a slide rod 89 which is mounted in a block 90, the block 90 being pivotally supported by a bracket 91 fastened to the frame 8. The slide rod 89 and the crank 84 have a common pin 92 connecting them, the pin 92 being operable in a vertical slot 93 in the slide bar 81.

In order to move the slide bar 81 from one extreme position to another, I provide trippers 94 which are secured to stops at the extreme ends of the travel of the carriage during its effective operation. The trippers operate to throw the dogs 86 and 87, whereby the slide bar 81 is moved. When the carriage has reached its extreme left hand position, as viewed in Figure 3, the tripper operates upon the dog 87 to turn the crank 84 so that the slide bar 81 is moved to its extreme left hand position. In this position the locking pin 80 coincides with the line of travel of the stud 79 and when the tripper bar 62 has moved the gag out of engagement with the stop to which the tripper 94 is attached, the locking pin 80 rides over the stud 79 and locks the gag out of stop engaging position so that the carriage may be freely moved along the track to its right hand position. At the extreme right hand of the carriage travel another tripper will then operate upon the dog 86 to throw the slide bar 81 toward the right, as viewed in Figure 3, so that the gag is disengaged from the locking pin and is free to reciprocate in the guide blocks 57 and 58 under the action of the spring 63 and the tripper bar 62.

As shown in Figures 15 and 16, the dogs 86 and 87 are duplicates, being arranged on the shaft in reverse sense. The dogs are formed of a body block 95 having a set screw 96 therein which engages the shaft 85. The pin 97 secures a tripper engaging member 98 to the body block 95. A stop pin 99 passing through the member 98 prevents the member from being moved to the left (Figure 15) without moving the body block 95 and the shaft 85; movement to the right is permitted, however, by reason of there being no portion of the body block extending into engaging position with the pin 99. Thus the dogs ride freely over the trippers in one direction but are effective for rotating the

shaft 85 when engaged in the opposite direction. This is true of both dogs.

The material 7 is supported by rolls 6 which are adjustable to various heights in the roll supporting standards 5. The standards 5 are provided with bearing slots 100 into which the shafts of the rolls may be readily slipped, the particular bearing slot employed being dependent upon the thickness and shape of the material 7.

In order to support the material 7 in true alignment with the dies which operate upon the material, it is necessary that the rolls 6 be adjustable vertically in small increments.

I provide such vertical adjustment by pivoting the standards 5 about a point 101 lying in the midline of the standards. The standards are maintained in a desired position by links 102 which are pivoted to the standards 5 at points equally spaced from the pivot point 101, the links 102 having their other ends connected to bell cranks 103 which are adjustable to vary the angular position of the standards 5.

The bell cranks 103 have their lower ends (Figure 7) connected together by links 104. All of the roll supporting standards and the linkages therefor are similar so that a number of rolls may be simultaneously adjusted by movement of the bell cranks.

I prefer to move all of the bell cranks by connecting the midpoints of all of the links 104 with control members 105.

There are two control members disposed with the links 104 intermediate, a pin 106 being spaced at the midpoint of the links 104 and extending through the members 105 in all cases.

Such an arrangement permits the roll supporting standards to be set up at any desired intervals and readily connected to the common control members.

The standards 5 are supported by base members 107 which form a part of the supporting standards 4, which support the track 3 upon which the carriage 2 is movable.

The control members 105, connecting all of the links 104, are connected together at a trunnion block 108, having trunnions 109 to which the members 105 are attached.

A bolt 110 passing through the trunnion block 108 is effective for moving the block 109 and thereby adjusting the angularity of all of the standards 5.

The bolt 110 has a head 111 abutting the trunnion block on one side while a capstan head 112, pinned to the bolt 110, abuts the trunnion block on the other side.

Rotation of the capstan head threads the bolt 110 into and out of a threaded block 112 bolted to a base portion 114, extending from the end standard 4.

In setting up the spacing machine, rolls 6 are selected which will best support the particular material 7 to be operated upon.

The rolls 6 are placed in the standards 5 in the bearing slots 100 which result in the material 7 being supported at an elevation slightly above the desired posi-

tion. The capstan head 112 is then rotated, adjusting the angularity of all of the standards 5, thereby bringing the rolls 6 to a slightly lower elevation than obtains when the standards are perpendicular. A very fine adjustment can thus be made insuring that the material 7 rests evenly upon the dies operating upon it.

While I prefer to adjust the rolls in the manner above described, due to evident convenience, simplicity of operation and accuracy, it will be understood that various other linkages and height adjusting means may be employed in order to bring all of the rolls into the same plane and in the desired relationship with the dies operating upon the material 7.

The channel 54 formed between the rack bar 50 and the back plate 55 is preferably of such depth that the stop 48 will be supported therein at a height at which the tops of the teeth 49 on the stop and tops of the teeth on the rack bar will coincide. Such a position of the stop takes advantage of the full length of the teeth 49, firmly supporting the stop to the utmost advantage. The operating face 56 on the stop extends a sufficient height above the teeth 49 that a good working surface is afforded for contact with the gag without interference of the teeth 49 and the gag. Although I prefer that the teeth have a pitch equal to an even division of an inch, for convenience in spacing, it will be understood that other pitches may be employed, depending upon whether the spacing is metric or in feet and inches. The faces 56 of the stops may be ground down, as indicated by the chain line F in Figure 12, to afford spacing at odd intervals not divisible evenly into the tooth pitch. I prefer that the teeth 49 on the stops be ground off slightly along the otherwise sharp edges to insure ample relief so that when the arm 51 is forced against the back strip 55 by the set screw 52 the teeth on the rack 50 will engage the teeth 49 to the fullest extent without interference. United States standard teeth have given good results in practice.

It will be noted that the arm 51 is ground away slightly at the top, at the portion which would normally coincide with the back plate 55 (Figure 14). This provision insures more than mere line contact between the arm 51 and the back plate 55; contact is effected in a region substantially half way between the top and bottom of the rack bar, insuring an even contact between the teeth of the rack bar and the stops.

The track 3 and rack bar 50 are preferably both secured to the same member to insure proper working cooperation between the gag and the stops. This member 115 is conveniently in the shape of a structural angle since this form provides a strong rigid frame which may be readily attached to the sup-

porting standard 4. The bearing blocks for the shaft 73, the back plate 55, and a spacing member 116, forming the bottom of a channel 54, into which the stops 48 are inserted, are all secured to an angle 117, one leg of which is secured to the leg of the angle 115. The track 3 has upper and lower rail members 3^a and 3^b which are spaced from the angle 115 by bars 3^c and 3^d to provide clearance for the flanged wheels 9 and 10. All of the elements of the track and framework supporting the rack bar are standard shapes which may be readily procured and assembled to form a rigid accurate bed for the track and support for the members acting upon the gag. Such a construction is economical and convenient, although other types of framework may be employed if desired.

The carriage 2 comprises a frame 8 in the form of a plate to which the supporting wheels 9 and 10 are attached. The various parts of the gripping mechanism are secured to the frame 8 by brackets. The gag guiding and controlling portions are secured to the frame 8 by bolts 57^a and 57^b by which the gag guide blocks are attached, all of the mechanism on top of the carriage being secured to the gag guide blocks.

Spacing the gripping mechanism a distance from the carriage permits gripping odd shapes, or wide flanged pieces, such as channels or Z bars without the carriage interfering with the material gripped.

Although I have described my spacing machine as having a carriage movable by the material being spaced, the operator pushing the carriage along the track as required, it will be understood that the machine may be operated just as efficiently by moving the material to be operated upon by machinery or automatic feeding means between successive operations of the machine tool used in connection with the spacing machine. Whether the material is moved by the operator or by a feeding mechanism is immaterial so far as the operation of the spacing machine is concerned. The improved material supporting device which I employ makes even comparatively heavy shapes easily movable by hand by the operator of the machine tool so that the spacing machine is a complete unit in itself with the supporting rolls, and no feeding device is ordinarily required within the limits of the machine. The machine is particularly adapted for comparatively light work by reason of its simplicity and rapidity of operation, although heavier shapes may be operated upon if the carriage and stops are made correspondingly strong to endure the repeated shocks encountered in the operation of the machine.

While I have illustrated and described the present preferred embodiment of my invention, it will be understood that the invention is not limited thereto, but that the invention

may be otherwise embodied within the scope of the following claims.

I claim:

1. In a spacing machine, jaws adapted to hold material therebetween, resilient means for holding the jaws closed, a rigid member interposed between the resilient means and the jaws, and means for varying the effective length of said member.
2. In a spacing machine, a fixed and a movable jaw adapted to hold material therebetween, a spring for holding the movable jaw closed upon the material, and controlled means for biasing the spring to close the movable jaw against the fixed jaw.
3. In a spacing machine, a pivoted and a fixed jaw adapted to hold material therebetween, a spring for urging the pivoted jaw against the fixed jaw, means maintaining the spring under load, and means for transferring the spring load to the pivoted jaw.
4. In a spacing machine, jaws adapted to hold material therebetween, a spring, means maintaining the spring under load, and means for transferring the spring load to a jaw, said transferring means including a cam interposed between the spring and the jaws, rotation of the cam causing variations in its effective length, transferring the spring load to a jaw.
5. In a spacing machine, jaws adapted to hold material therebetween, means for closing the jaws comprising a cam surface and a cam follower adapted to ride the cam surface and move one jaw relative to the other, a link for moving the cam follower, resilient means operable upon the link to hold the cam follower in operative position maintaining the jaws closed, and means interposed between the resilient holding means and the link for rendering the resilient means operative or inoperative upon the link.
6. In a spacing machine, a track, a carriage movable along the track, stops at predetermined intervals along the track, a gag on the carriage adapted to engage the stops and stop the carriage at predetermined intervals, means normally urging the gag into stop engaging position, means for automatically disengaging the gag from successive stops, and means for locking the gag out of stop engaging position during the return travel of the carriage after a spacing operation.
7. In a spacing machine, a carriage movable along a track, a stop along the track, a gag on the carriage movable into and out of alignment with the stop, means normally urging the gag into stop engaging position, a locking pin for holding the gag out of stop engaging position, said locking pin being movable into or out of locking position, and means effective at different positions of the carriage for moving said locking pin.
8. In a spacing machine, a carriage movable along a track, a gag adapted to engage

stops disposed along the track, a spring normally urging the gag into stop engaging position, a locking pin for holding the gag out of stop engaging position, a stud on the gag engageable by the locking pin, a slide bar carrying the locking pin whereby the pin is movable into and out of cooperative relationship with the stud, said locking pin being effective for holding the stud against movement in a direction toward stop engaging position of the gag, and means for moving the slide bar.

9. In a spacing machine, a gag adapted to engage a stop, a spring normally urging the gag into stop engaging position, guide blocks holding the gag substantially transversely of the carriage when the gag contacts with a stop, and a spring throwing the gag out of transverse position upon disengagement of the gag with the stop whereby the end of the gag is displaced from the working face of the stop and reengagement of the gag with the same stop is prevented.

10. In a spacing machine, a carriage, a stop for positioning the carriage, a gag on the carriage and movable transversely of the direction of movement of the carriage for engagement with the stop, means for moving the gag out of engagement with the stop, and means effective upon such movement for advancing the gag past the stop independently of the carriage.

11. In a spacing machine, a plurality of substantially parallel walls forming a groove, a stop insertable in the groove, and means comprising an arm hinged on the stop for exerting pressure on the walls of the groove.

12. For use with a spacing machine having a rack bar, a stop for engaging the rack bar, and means for holding the stop in engagement with the rack bar, said holding means including an arm hinged to the stop and a set screw for moving the arm about the pivot point, thereby increasing the effective thickness of the stop in the direction perpendicular to the rack bar engaging portion.

13. For use with a spacing machine having a rack bar, a stop having teeth, and means for holding the teeth in cooperative engagement with the rack bar, said holding means including an arm hinged to the stop and a set screw for moving the arm about the pivot point, thereby increasing the effective thickness of the stop in the direction of the depth of the teeth.

14. In a spacing machine, a carriage movable along a track, a gag on the carriage adapted to engage stops whereby the carriage is stopped at predetermined intervals along the track, spring means on the carriage normally urging the gag into stop engaging position, means along the track for periodically moving the gag out of engaging position, means on the carriage for locking the gag out of stop engaging position during the return

travel of the carriage after a spacing operation, and means for rendering said locking means inoperative during the spacing operation whereby the means urging the gag into stop engaging position is rendered operative.

15. A stop for use in a spacing machine in cooperation with a rack bar and a backing surface spaced from the rack bar, said stop having teeth for cooperation with the rack bar, and an arm adapted to engage the backing surface, said stop having an engaging face for determining the position of the carriage of the spacing machine, the face extending above the rack bar and being substantially perpendicular thereto, the stop being chamfered from the face on the toothed side of the stop.

16. In a spacing machine, a track, a carriage movable along the track, a plurality of stops adjacent the track, a gag on the carriage adapted to engage the stops, means for locking the gag out of stop engaging position when the carriage is moving in one direction along the track, and means for releasing the gag locking means when the carriage has reached the end of its travel, said gag locking means including a locking pin carried by a slide bar whereby the pin is movable into and out of locking position, and dogs for moving the slide bar, the dogs being operable by trippers disposed at the extremities of the travel of the carriage, one of said trippers being adapted to move the slide bar and place the locking pin in locking position, and the other of said trippers being effective for moving the slide bar and rendering the locking pin inoperative.

17. In a spacing machine, a carriage movable along a track, a stop along the track, a gag movable into and out of alignment with the stop, means normally urging the gag into stop engaging position, a locking pin for holding the gag out of stop engaging position, said locking pin being movable into and out of locking position, trippers disposed at the extremities of travel of the carriage for throwing the locking pin into and out of locking position.

18. In a spacing machine, a carriage movable along a track, a stop along the track, a gag movable into and out of alignment with the stop, means normally urging the gag into stop engaging position, a locking pin for holding the gag out of stop engaging position, means for moving said locking pin into and out of locking position comprising a plurality of dogs and a spring pressed toggle, and tripping means disposed at the extremities of travel of the carriage for engaging said dogs and for throwing the locking pin into and out of locking position.

19. Material supporting means for a spacing machine comprising a plurality of rolls, standards for supporting said rolls, said standards having a plurality of roll support-

ing bearings at different roll heights, and means for simultaneously changing the positions of the standards.

20. Material supporting means for a spacing machine comprising a plurality of rolls, standards for supporting said rolls, said standards having a plurality of roll supporting bearings at different heights, and means comprising a plurality of simultaneously actuated bell cranks for changing the positions of the standards.

21. A stop for use in a spacing machine in cooperation with a rack bar and a backing surface spaced from the rack bar comprising an arm secured to the stop and disposed to engage the backing surface substantially midway between the top and bottom of the rack bar.

22. A roll structure comprising a roll, and pivotally mounted supporting plates at opposite ends of said roll for varying the position of the roll by the rotation of said plates about their pivotal mountings, each of said plates having a plurality of roll supporting means.

23. A roll structure comprising a roll, and pivotally mounted supporting plates at opposite ends of said roll for varying the position of the roll by the rotation of said plates about their pivotal mountings, each of said plates having a plurality of roll engaging notches disposed about the periphery thereof.

In testimony whereof I have hereunto set my hand.
